UNITED STATES PATENT OFFICE.

HARBER C. BEARDSLEY, OF LAKewood, OHIO.

PHYSICIAN'S TABLET-HOLDER.

977,583.

Specification of Letters Patent.

Patented Dec. 6, 1910.

Application filed August 4, 1909. Serial No. 511,175.

To all whom it may concern:

Be it known that I, HARBER C. BEARDSLEY, a citizen of the United States, residing at Lakewood, in the county of Cuyahoga and State of Ohio, have invented a certain new and useful Improvement in Physicians' Tablet-Holders, of which the following is a full, clear, and exact description.

This invention relates to a holder for medicinal tablets adapted to be conveniently carried by a physician.

The object is to provide a holder which will protect the tablets therein, which will enable the physician to see how many tablets he has, and which will enable him to deliver with certainty said tablets, one at a time, into any suitable receptacle, without touching them with his hands.

The holder is especially adapted for holding hypodermic tablets, and delivering them one at a time into the syringe.

The invention consists of a tube having an open end through which it may be filled and having at the other end a metal cap which serves as a slide guide, and an ejecting slide mounted on said cap and adapted to eject the tablets one by one from the tube, a stopper for closing the normally open end of the tube, and a light coil spring compressed between the stopper and the column of tablets whereby they are held in operative relation with the ejecting slide.

It also consists in the more specifically defined combinations of parts as recited in the claims.

In the drawing, Figure 1 is a perspective view of a device embodying the invention; Fig. 2 is a longitudinal section thereof; and Fig. 3 is a longitudinal section of the cap carrying end of said device, the section being at right angles to the section shown in Fig. 2. These drawings show the device as of about three times the size required for hypodermic tablets.

Referring to the parts by letters, A represents a glass tube, one end of which is to be closed by a stopper C. To the other end of this tube a cap B is secured, said cap comprising a band b which tightly embraces the tube and a laterally extended plate b' having overturned edges b² to form a guideway.

D represents an ejecting slide mounted in said guideway,—that is to say, projecting beneath the overhanging edges of said plate. At its ends this ejecting slide is furnished with the bent down fingers d', d², adapted

to engage the cap and thereby to limit the movements of said slide. In the slide is an outwardly pressed pocket d of such internal size as corresponds substantially with the size of the tablets which the holder is adapted to contain. Normally,—that is to say, when one of the fingers on the slide engages with the cap, this pocket will be alined with the tube. When the slide has been moved far enough to move the other finger into engagement with the cap, this pocket will have moved laterally so that a tablet therein may fall out.

After the tube has been charged with as many tablets as it should contain, a very light spring is placed therein against the bottom tablet and then the stopper C is inserted, thereby compressing this spring. The spring thereby serves to move the column of tablets normally in the tube so as to cause the upper tablet to enter the described pocket. If desired, the stopper may be sealed into the tube as, for example, by softening and bending over some parts of the lower edge of the glass tube as shown in Fig. 2. The described tablet holder is one which permits the physician to observe whether his holder contains as many tablets as he is apt to need. It protects said tablets from dirt; it prevents them from being broken by attrition against one another, and it also enables him to eject therefrom one tablet at a time and to deposit it in the open end of a hypodermic syringe or into any other receptacle, without being obliged to touch it with his hands.

The device is carefully made with the joints sufficiently air tight to prevent access to its interior of any material quantity of fresh air, not more at any one time than enough to compensate for the withdrawal of a tablet, thereby protecting the remaining tablets from possible too rapid deterioration through frequently admitted considerable bodies of fresh air acting upon any of their chemical properties.

Having described my invention, I claim:—

1. In a physician's tablet holder, the combination of a tube, a stopper for closing one end thereof, a spring resting upon said stopper, a band embracing the delivery end of the tube, an integral lateral plate on said band and extending away from it at one side, bent overhanging flanges forming guide grooves on the lateral edges of said plate, a longitudinal slot in the extension

of said plate, with a slide plate mounted in said guide grooves and closing the delivery end of the tube, stops formed at each end of said slide to limit its reciprocation, the rear one of which lies in the said slot of the lateral plate, an outwardly pressed pocket in said slide plate opening inwardly to the tube and adapted to be held in alinement therewith by the front stop or moved laterally therefrom to a plane beyond the tube such movement being limited by the rear stop in said slot.

10 2. In a physician's tablet holder, the combination of a glass tube, a stopper for closing one end thereof and immovably sealed in place, as described, after the tube is charged with tablets, a spring resting upon said stopper, a band embracing the delivery end of the tube and rigidly secured thereon, 15 a lateral plate rigidly secured on said band

and extending away from it at one side, overhanging flanges forming guide grooves on the lateral edges of said plate, with a slide plate mounted in said guide grooves and closing the delivery end of the tube, stops formed at each end of said slide to limit its reciprocation, an outwardly pressed pocket in said slide plate opening inwardly to the tube and adapted to be held in alinement therewith by the front one of said stops or moved laterally therefrom to a plane beyond the tube being limited in such movement by the rear one of said stops.

20 In testimony whereof, I hereunto affix my signature in the presence of two witnesses.

HARBER C. BEARDSLEY.
